Primary Examiner—Terry A. Wallace*Assistant Examiner*—R. Barkai*Attorney, Agent, or Firm*—Richard B. O'Planick; Lisa B. Riedesel[57] **CLAIM**

The ornamental design for a toy vehicle, as shown and described.

DESCRIPTION

FIG. 1 is a top right front perspective view of a toy vehicle showing my new design;

FIG. 2 is a top plan view thereof;

FIG. 3 is a front elevational view thereof;

FIG. 4 is a rear elevational view thereof;

FIG. 5 is a left side elevational view thereof; the right side elevational view being a mirror image; and,

FIG. 6 is a bottom plan view thereof.

The broken line showing of the wheels and steering wheel in FIGS. 1-6 is for illustrative purposes only and forms no part of the claimed design.
